(57) **CLAIM**

The ornamental design for a case for electronic communications device, as shown and described.

DESCRIPTION

FIG. 1 is a perspective view including the rear, bottom, and side of a case for electronic communications device showing our new design;

FIG. 2 is a perspective view including the front, bottom, and the opposite side of the case for electronic communications device of FIG. 1;

FIG. 3 is a rear elevation view of the case for electronic communications device of FIG. 1;

FIG. 4 is a front elevation view of the case for electronic communications device of FIG. 1;

FIG. 5 is a side elevation of the case for electronic communications device of FIG. 1;

FIG. 6 is an opposite side elevation view of the case for electronic communications device of FIG. 1;

FIG. 7 is a top plan view of the case for electronic communications device of FIG. 1; and,

FIG. 8 is a bottom plan view of the case for electronic communications device of FIG. 1.
